CLAIM

The ornamental design for a lens assembly for welding mask, as shown and described.

DESCRIPTION

FIG. 1 is a front perspective view of a lens assembly for welding mask showing my new design;

FIG. 2 is a front elevation view of the lens assembly for welding mask of FIG. 1;

FIG. 3 is a rear elevation view of the lens assembly for welding mask of FIG. 1;

FIG. 4 is a right side view of the lens assembly for welding mask of FIG. 1;

FIG. 5 is a left side view of the lens assembly for welding mask of FIG. 1;

FIG. 6 is a top view of the lens assembly for welding mask of FIG. 1; and,

FIG. 7 is a bottom view of the lens assembly for welding mask of FIG. 1.

The broken lines shown in the drawings represent portions of a lens assembly for welding mask that form no part of the claimed design.
